UNITED STATES PATENT OFFICE.

SAMUEL B. WILLIAMS, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed July 16, 1924. Serial No. 726,268.

This invention relates to telephone exchange systems, but more especially to that class of systems wherein automatic switches and apparatus are employed for the purpose of controlling and completing conversational connection.

The invention is particularly applicable to systems adapted to handle toll or long distance connections. The arrangement in these systems is of such a nature that the completion of certain classes of connections is generally under control of an operator. The operator thus serving to complete connections has allotted for use certain portions of the exchange apparatus which function only in this class of service, that is to say, the operator controls the operation of certain inter-switches, and the selection of certain inter-connecting trunks, these switches and trunks being used exclusively in handling particular classes of calls, such as long distance toll calls. This arrangement may also be employed by so called verifying or checking operators when circumstances require that the condition of a particular line be verified. In addition, the exchange is provided with other switches and interconnecting trunks to take care of the usual interoffice or local traffic.

Accordingly, it is an object of the invention to increase the efficiency of interconnecting trunks by allowing certain of these trunks to be used indiscriminately in the completion of local or interoffice calls and also in the completion of connections under control of an operator.

A feature of the invention is the manner of distributing trunks between different groups of switches, the switches of each group serving to complete different classes of connections, while certain of the trunks are capable of completing connections independently of the class of switch taken for use.

Other inherent features and advantages of this invention will become apparent after a consideration of the following detailed description and the appended claims.

The drawing showing a preferred form of carrying out the invention consists of representations, part schematically and part in detail, of switching and controlling apparatus and comprises Figs. 1 to 5, inclusive. These figures when arranged in the order

shown in Fig. 6 disclose a telephone system embodying the features of the invention in sufficient detail to give an understanding thereof.

Fig. 1 in the upper portion illustrates schematically apparatus for extending a local connection, including a line switch and a district selector switch. In the lower part of this figure is shown schematically a sender selector switch and one of a number of registering and controlling senders. The portion of this figure enclosed within the dotted rectangle is a diagrammatic representation of an operator's position and the corresponding position equipment. Extending through the central part of this figure is disclosed one of a number of trunks incoming from a distant office.

Fig. 2 in the upper portion shows one of a number of incoming selector switches adapted to extend the usual local and inter-office connections. In the lower part of this figure is shown an incoming selector switch adapted to extend connections under control of the operator's equipment, shown in Fig. 1.

Fig. 3 illustrates a portion of a final or connector switch having access to called subscribers' lines.

Fig. 4 shows a portion of one of a number of controlling markers, and also a connecting device for associating a selected sender with an idle marker.

Fig. 5 illustrates schematically frame and trunk connectors for associating the markers with the incoming and final switches.

The system disclosed herein is adapted to function in the handling of both local calls and calls originating in a distant office as well as calls from distant offices requiring the intervention of an operator.

The local lines 100 terminate in coordinate line switches 101, which in their automatic operation are adapted to extend calling lines to trunks, as 102, leading to district selector switches, as 103. The district selector switch is thereupon selectively operated under control of a marker to extend the calling line to an idle trunk, such as trunk 115, which leads to an incoming selector switch, as 200. These trunks terminate in vertical rows of contacts on the incoming selector switches. For example,

trunk 115 appears in vertical row of contacts 213, while the remaining trunks would appear in still other vertical rows similar to rows 213 and 214. The incoming switches 5 200 are adapted to be selectively operated under control of an incoming marker, such as partly shown in Fig. 4, to further extend the calling line to an idle one of the trunks 219, 220, etc. which lead to connector 10 switches having access to the desired line.

The connector switches are divided into a number of groups, each group having access to a particular portion of the total number of subscribers' lines. The group 15 of trunks appearing in vertical row 215, comprising trunks 217, 218, etc. extend to, and have an appearance in connector switches of a particular group. The group of trunks appearing in vertical row 216 20 comprising trunks 219, 220, etc. extend to, and have an appearance in a second group of connector switches, one switch of this second group, switch 300, being shown. It will be observed that the trunk 220, for example, appears in vertical row 301 in connector switch 300 and has access to a link in each of the units sections of this latter switch. Likewise, other groups of trunks leading from the incoming switch 200 have 25 an appearance in still other connector groups, each of the trunks in a group being multiplied to appear in all of the incoming switches composing a group.

In addition to the equipment provided 30 for the completion of local connections the office is also provided with operator's positions and equipment, as shown in Fig. 1. The trunks, such as trunk 103, incoming from distant offices may serve to extend toll 35 or long distance connections or for other similar purposes. These trunks it will be observed appear in vertical rows of contacts of a special group of incoming selector switches, one of which, switch 201, is shown. 40 The trunk 106, for example, which is partially shown, appears in vertical row of contacts 202 in switch 201. Another trunk of similar nature 107 is shown appearing in vertical row 203. At each operator's position is provided a key set 105, an assignment key 112 and a release key 113. The assignment and release keys are individual to each 45 of the trunks 106, 107, etc.

The special incoming switches, as 201, 50 have access to groups of operator's trunks extending to the several groups of connector switches. For example, the vertical row of contacts 205 may include a number of these operator's trunks all leading to the same group of connector switches in which switch 300 is included. The trunks appearing in vertical row 206 in like manner lead to another group of connector switches.

It will be observed that trunk 220 appearing 55 in row 205 of switch 201 is identical

with the trunk which is multiplied to appear in vertical row 216 of the local incoming switch 200. The distribution of the trunks in switch 200 is such that trunk 220 is the last trunk to appear in vertical row 70 216. In a similar manner the next operator's trunk 222 appearing in row 205 will be multiplied to appear as the last trunk in a different row of contacts in the same or a different local incoming switch. This arrangement holds true of the remaining trunks in row 205, each trunk being identical with the last trunk in a vertical row 75 of contacts in a local incoming switch, giving access to the connector group, which includes a switch 300. Thus, trunks 220, 222, 223, and 224 are each, respectively, the last trunk in different groups of trunks leading from incoming selector switches to the same group of connector switches, which includes 80 switch 300. These several operator's trunks all appear in the same vertical row of contacts 205 in switch 201. In a similar manner the operator's trunks appearing in vertical row 206 of switch 201 are identical 85 with the last trunks in corresponding groups of trunks leading from the local incoming switches to a second connector group. This same arrangement may hold true for as many connector groups as there 90 are provided.

Thus, it will be seen that each of the trunks 220, 218, etc. may serve to extend the usual local and interoffice connections or interoffice connections where an operator is 95 required.

Each of the operator's trunks in any one group is arranged to appear before corresponding horizontal links in each of the several connector switches of a group. Each 100 trunk, however, appears in a different vertical row of contacts in these connector switches. For example, trunk 220 appears before horizontal links 313, 314, etc. in vertical row 301 of connector switch 300 and 105 in a similar manner before the corresponding links in other connector switches of this same connector group. The second trunk 222 is also accessible to links 313, 314, etc. but only by means of vertical row of contacts 110 302. This arrangement holds true with respect to the remaining trunks appearing in row 205 of switch 201 and also 115 with regard to the trunks in vertical row 206. In this latter case, however, the trunks appear in a different connector group from 120 that which includes switch 300.

Each of the local trunks 102 and the incoming trunks 106 may be associated with 125 idle register senders, one of which, sender 107 is shown diagrammatically, by means of sender selector switches as 104. In practice there may be two types of senders 107 one to be used for local connections and the other to be used for incoming calls. Ac- 130

cordingly the local trunks 102 may be associated with one kind of sender through one sender selector switch 104 whereas the incoming trunks 106 may be associated with the other kind of sender through another sender selector 104. For convenience in the drawing, however, both local and incoming trunks have been shown as appearing in the single sender selector frame 104 and no attempt has been made to disclose the details of the different types of senders. Each of the several register senders, such as sender 107, may be associated with an idle one of a number of markers, part of one of these markers being shown in Fig. 4. For this purpose a sender connecting device 400 comprising a number of multi-contact relays is provided for connecting the selected sender to the first idle incoming marker.

The called line numerical record as registered in the sender 107 is transferred to the marker which thereupon causes the selective operation of an incoming and a final switch to complete the connection to the wanted line. After the record has been received the marker is associated with the proper incoming switch by means of the connector 500. The test relays 401 in the marker are thereby connected to the test conductors of the horizontal links in the proper incoming switch. In case the connection being extended is one involving a local line and thereby entailing the use of a switch such as 200, the marker is also associated with the trunks outgoing from this switch to the proper group of connector switches by means of the trunk connector 501.

Moreover, the marker is associated by means of the connecting device 502 with the particular connector switch in the connector group having access to the group of lines which includes the wanted line. As a result of this association the marker testing mechanism is connected to the horizontal links in a particular section of the selected connector switch, as determined by the units digit of the called line designation. With the marker thus associated a three-point test is made to determine an idle link in switch 200, an idle trunk leading from switch 200, and an idle link in switch 300. Having determined this available path the incoming and connector switches are operated to complete the extension of the calling line to the called line.

Should the call be of such a nature as to require the use of a trunk as 106 and the consequent services of an operator the connection is extended through a switch, similar to switch 201, to one of the operator's trunks 220, 222, etc. Since the number of these latter trunks is comparatively small the trunk connector 501 is replaced by relays such as 503 and 504, etc. for the purpose of associating a limited number of marker test

relays in accordance with the size of the selected group of operator's trunks.

Each of the relays 503, 504, etc. is individual to a connector group, and consequently to a connecting device as 502. For example, relay 504 is individual to device 502, while relay 503 would be individual to a different connecting device associated with a second connector group.

The marker testing mechanism is so arranged that there is a set of test relays for each of the trunks in a group leading from the local incoming switch 200 to the several connector switches. Inasmuch as the number of operator's trunks in a group is considerably less than the trunks in a group leading from the local incoming switches, relays 503, 504, etc. are provided for connecting the test conductors of these small trunk groups to the corresponding marker test relays. If the called line occurs in the group of connector switches including switch 300, the connecting device 502 will have been operated to associate the marker with the links in section 310 of switch 300. The selective operation of device 502 serves to identify to the marker the group of trunks leading from switch 200 by causing the operation of a relay such as 504. Should the called line be accessible by the switches of another connector group then a different relay such as 503, would be operated to identify to the marker the proper group of trunks leading from switch 201 to this connector group.

The selective switches illustrated in the drawing may be of the type shown and described in detail in the application of Charles L. Goodrum and John N. Reynolds, Serial No. 486,442, filed July 21, 1921, Patent No. 1,515,735, granted November 18, 1924, and also further described in the application of S. B. Williams, Serial No. 596,179 filed October 23, 1922, Patent No. 1,517,331, granted December 2, 1924. Inasmuch as a detailed description of the structure and operation of the senders 107, connecting devices 400, the markers and the frame and trunk connectors shown in Fig. 5, is not necessary for a complete understanding of the present invention, these several portions of the exchange apparatus have been illustrated in a comparatively diagrammatic form. For a more complete description of the operation of these devices, reference may be had to the application of S. B. Williams, Serial No. 707,795, filed April 21, 1924.

Connections involving an operator.

It will be assumed for the present that a connection originating in a distance office requires extension to the called line 307. In any well known manner, the operator's attention is called to the fact that the completion of the call requires her intervention.

She thereupon assigns an idle trunk such as trunk 106 and operates the assignment key 112, individual thereto. The operation of key 112 results in the association of a key set such as 105 with an idle register sender such as 107 by means of the automatic operation of sender selector switch 104. The operator at the distant office upon receiving the assignment of trunk 106 extends the connection thereover in the usual manner and also communicates to the local operator the designation of the wanted line. On learning this designation, the local operator then proceeds to set up a record thereof on the key set 105. When the designation has been thus set up it is transferred by means of switch 104 to the registers of sender 107 (not shown). For a detailed description of the manner in which these latter operations are effected, reference may be had to the application of E. S. Gibson, Serial No. 656,742, filed August 10, 1923, Patent No. 1,559,244, granted October 27, 1925. After the record has been thus transferred to the sender registers, sender connector 400 is operated to associate the selected sender with an idle incoming marker. Assuming the marker shown in the drawing to be the first idle one, upon seizure thereof the numerical record is again transferred from the sender registers to the corresponding marker registers. The record as thus received by the marker is therein translated, and the proper connecting device as 502, is actuated to associate the marker with the proper group of connector switches which includes switch 300. Assuming the device 502 shown is the one to be used, then relay 505 which is individual to the selected marker is operated. In addition, relay 506 which is individual to the section 310, in connector switch 300, as determined by the units digit of the wanted line is operated. The translation of the called line record in the marker at this time causes the operation of vertical magnet 306, individual to the row of contacts 304 in which the called line 307 appears.

As soon as the marker has been associated with the sender, relay 402 is operated. The operation of relay 402 completes a circuit for relay 406. This circuit may be traced from battery through the winding of relay 406, contact 451, contacts of connector 400, conductor 452, left armature and back contact of relay 111, conductor 453, contacts of connector 400 to ground at an armature of relay 402. At this time also, the proper frame connector 500 is selected and operated to thereby associate the marker with the horizontal links of switch 201. The actuation of connector 500 is initiated by the operation of relay 507 which energizes in a circuit traceable from battery through its winding, conductor 551, armature and contact of relay 406, armature and back contact of relay 405, to ground at an armature of relay 402. Relay 507 is individual to the marker shown. If some other marker had been selected then the corresponding start relay as for example relay 537 would be operated to bring about the operation of the corresponding multi-contact relay 538. In the manner described in detail in the above mentioned application of E. S. Gibson, Serial No. 656,742, filed August 10, 1923, Patent No. 1,559,244, when the connection has been extended to switch 201, vertical magnet 206 is operated, to prepare the contacts in vertical row 202. The operation of magnet 206 results in the actuation of multi-contact relay 509 which is individual to the switch 201. With relays 509 and 510 operated, certain of the test relays 401 are connected to the test conductors of the links in switch 201. Since the called line 307 is reached by the group of switches including switch 300, and since the switches in this group are accessible by the trunks leading from vertical row 205, the corresponding vertical magnet 207 is operated.

A test is now made to determine an available path through switches 201 and 300 to the called line 307. This path comprises an idle link in switch 201 giving access to an idle trunk terminating before a link as 313 in switch 300. This path also includes an idle link in switch 300 before which the called line appears.

Before the marker can make a test of the available paths to the called line, it is necessary to associate said marker with the selected group of operator's trunks. At the time frame connector 500 is operated, and subsequent to the association of register sender 107, with the marker, sender relay 109 is actuated to indicate that the connection requires the services of an operator. The circuit for relay 109 may be traced from battery through its winding and normal contacts, conductor 456, contacts of connector 400, conductor 457, contacts of relays 510 and 509 returning thence to conductor 458, to ground at an armature of relay 402. Relay 109 locks through its winding and locking contact to ground at the armature of holding relay 108 which has been previously energized. When relay 109 operated, a circuit was completed from battery through the winding of relay 404, conductor 454, contacts of connector 400, conductor 455, left armature and contact of relay 109 to the grounded conductor 453. Relay 404 operates relay 504 in a circuit traceable from battery through the winding of relay 504, contact of relay 505, conductor 552, to ground at the outer armature and contact of relay 404. The operation of relay 504 serves to connect certain of the marker test relays to the sleeve contacts of the trunks appearing in row 205.

The testing circuit for the links in

switches 201 and 300 and the inter-connecting trunks will now be described. The circuit for testing horizontal link 228 may be traced from battery through the left winding of relay 411, contact of relay 407, conductor 553, contacts of connector 500, conductor 251 to the test conductor of link 228. In a similar manner, test circuits may be traced from battery through the left windings of relays 410, 409 and 408 to the test conductors of links 227, 225, and 226 respectively. The circuit for testing operator's trunk 220 may be traced from battery through the right winding of relay 411, contacts of relay 407, right inner armature and contact of relay 419, conductor 459, armature and contact of relay 504, to conductor 256. If trunk 220 is busy, either relay 208 or 209 or both are operated thus placing ground on the sleeve conductor of trunk 220, and conductor 256. In like manner, test circuits for the operator's trunks 222, 223 and 224, may be traced through the right windings of relays 410, 409 and 408 respectively. The test relays 408, 409, etc. are so adjusted that they will be operated if either one winding alone or both windings together are energized. Should either a trunk or a link to which a test relay is connected be busy, ground potential is found thereon to cause the actuation of the corresponding test relay.

Lastly, a test is made to ascertain the condition of a link such as link 313 in the connector switch 300 having access to line 307. The circuit for this purpose may be traced from battery through the winding of relay 415, conductor 460, contacts of connector 502, conductor 557 to the test conductor of link 313. If this link is busy, ground potential exists on the test conductor and causes the operation of relay 415. It will be assumed that link 228, trunk 220 and link 313 are simultaneously idle and links 225, 226 and 227 and the corresponding trunks 222, 223 and 224 are all busy. Consequently, test relays 408, 409 and 410 are operated and relays 411 and 415 are normal.

As soon as the above testing operations have been completed, a circuit is closed from ground through the right inner armature and front contact of relay 404, armature and back contact of relay 415, left armatures and front contacts of relays 408, 409 and 410 in series, left armature and back contact of relay 411, to battery through the winding of relay 419. The operation of relay 419 completes a circuit from battery through the winding of magnet 305, conductor 351, right armature and contact of relay 504, conductor 554, right outer armature and contact of relay 419 to ground at an armature of relay 402. Magnet 305 in operating rotates rod 370 to prepare the contacts of vertical row 301 in which the idle trunk 220 terminates.

The operation of relay 419 also completes energizing circuits for magnets 229 and 318. The circuit for operating magnet 229 may be traced from battery through the right winding thereof, conductor 252, contacts of connector 500, conductor 555, left inner armature and contact of relay 419 to ground at an armature of relay 402. Magnet 229 rotates the corresponding horizontal bar (not shown), and completes the connection of trunk 106 with trunk 220.

The circuit for operating magnet 318 may be traced from battery through the right winding thereof, conductor 352, contacts of connector 502, conductor 555, to ground through the left inner armature and contact of relay 419. Magnet 318 rotates the associated horizontal bar (not shown) and effects connection of trunk 220 by means of link 313 with the called line 307.

When relay 419 operated, it also completed a circuit from ground at the left inner armature and contact of relay 402, armature and back contact of relay 403, middle armature and contact of relay 419, conductor 462, left outer armature and contact of relay 504, conductor 556, to battery through the winding of relay 210. Since connection through the incoming switch 201 has been completed, relay 114 at the operator's position is energized in a circuit traceable from battery through its winding, sleeve conductor of trunk 106, contacts of switch 201, conductor 251 contacts of connector 500, conductor 553, innermost front contact of relay 407, left outer contact of relay 419, to ground at an armature of relay 402. Relay 407 is operated at this time in the manner described in detail in the application of S. B. Williams, Serial No. 707,795, filed April 21, 1924. Relay 114 immediately locks to ground at the release key 113. The operation of relay 114 also maintains this same ground as a busy condition on the sleeve conductor of trunk 106 which serves as a holding circuit for magnet 229 subsequent to the release of the marker. This same ground is extended through contacts in vertical row 205 to conductor 253 of trunk 220, through the right winding and normal contacts of relay 208 to battery. Relay 208 locks in a circuit traceable from battery through the winding of relay 209, left outer armature and front contact of relay 210, right inner armature and front contact, and right winding of relay 208 to the grounded conductor 253. Slow release relay 209 operates in this last traced circuit. An obvious holding circuit for relay 210 is now completed to ground at the armature of relay 209.

In the manner described in detail in the above-mentioned application of S. B. Williams, Serial No. 707,795, filed April 21, 1924, since the called line has been seized,

the marker is released. The release of the marker also brings about the release of the operated vertical magnets in switches 201 and 300 and the subsequent release of the various frame and trunk connectors.

Prior to the actuation of horizontal magnet 318 the test horizontal magnet 319 was operated to determine the idle condition of the called line. For a detailed description of the manner in which this test is made, and also of the various detailed operations hereinbefore referred to, but not fully described reference may be had to the above-mentioned application of S. B. Williams, Serial No. 707,795, filed April 21, 1924.

As soon as the marker is released and the vertical magnets 206 and 207 are deenergized the connection through switch 201 is maintained by magnet 229 which is now held in a circuit traceable from battery, through both its windings in series, contacts of switch 201 to the grounded sleeve conductor of trunk 106. In a similar manner connector switch 300 is maintained operated after the release of magnets 305 and 306, by the continued energization of magnet 318 which is held in a circuit traceable from battery, through both windings in series, lowermost conductor of link 313, contacts of row 301, conductor 353, right outer armature and front contact of relay 210 to ground at the armature of relay 209. This same ground is extended by means of conductor 321 through contacts of switch 300, to the sleeve conductor of line 307 rendering trunk 220 and the line 307 busy. When it is desired to release the connection the operator restores key 113 thus removing ground from the sleeve conductor of trunk 106. The removal of ground from trunk 106 causes the release of magnet 229, thus releasing the incoming switch 201. The release of the incoming switch removes ground from conductor 253 thus opening the holding circuit of relay 209 which releases if the called subscriber has disconnected. Should the called subscriber still maintain the receiver off the switchhook subsequent to the release of relay 208, a substitute locking circuit for relay 209 is completed through the winding and locking contact of said relay, middle armature and back contact of relay 208, over the ring conductor of trunk 220, through the contacts of switch 300, through the called subscriber's loop returning thence by means of switch 300 and the tip conductor of trunk 220, left inner armature and front contact of relay 209 to ground at the armature of relay 208. The interrupter 212 is provided to limit the time the called subscriber can thus maintain the connector switch in its operated condition, subsequent to the release of the incoming switch. When interrupter 212 closes its lower contact, ground is connected through the contacts

of relays 208, and 209 through the normal contacts and winding of relay 211 to battery. Relay 211 operates and locks to ground at the armature of relay 209. At the end of a predetermined interval when interrupter 212 closes its upper contact ground is connected through the left armature and contact of relay 211, to battery through the left winding of relay 208 which operates.

The operation of relay 208 at this time opens the locking circuit for relay 209 which begins to release. When relay 209 has completely retracted its armatures, holding ground is removed from conductor 321, and relay 210 is released thus bringing about the release of magnet 318 and switch 300.

Associated with the key set 105 is a "no test" key 119 by means of which the operator is enabled to extend the connection to a subscriber's line even though this line may be otherwise busy at this time for the purpose of informing the subscriber that a second call, such as a long distance or toll call, is awaiting. If the waiting call is of sufficient importance, the called subscriber may wish to discontinue the prior conversation to take care of the more important call. Should, however, the called subscriber deem the second call of insufficient importance to warrant discontinuance of the first call, it is necessary that the operator release the second extended connection. In order to release the various trunks and switches employed in this second connection, the operator restores release key 113. The restoration of key 113 removes ground from the sleeve conductor of trunk 106, thus releasing incoming switch 201 and final switch 300. However, since trunk 106 has been extended to a busy line, the sleeve conductor of which is grounded, the tendency of this ground is to maintain switches 201 and 300 in their previously operated condition, thus reducing the operating efficiency of its switches.

To obviate this condition, the circuits are so arranged that the operator may extend a connection to a caller subscriber's line and may thereafter release this extended connection regardless of the continued busy condition of the called line.

It will be assumed therefore that the operator is extending a call of a toll or long distance character which it is required, shall be extended to the called line regardless of this busy condition. Accordingly to anticipate the busy condition of this called line, the operator upon receiving the called designation operates the "no test" key 119 whereby the "no test" relay 403 located in the marker is subsequently operated. In this instance, however, since relay 403 is operated the operating circuit for line busy test relay 412 is opened at the left contact of relay 403, and the connection through switches

301 and 300 proceeds in the manner already described when line 307 was assumed idle. When the connection is later completed through switches 201 and 300, relay 210 fails to operate as previously described, since the circuit for energizing this relay is now open at the contact of relay 403.

In a manner already described, relay 208 operates over a circuit traceable through its right winding, and immediately locks over a circuit traceable from battery at the left outer armature and back contact of relay 210, locking contact and right winding of relay 208, and thence to the grounded sleeve conductor of trunk 106. Since relay 210 remains normal, the previously traced circuit for relay 209 is opened and this latter relay also remains normal. Under this condition, switch 300 is now held by means of a circuit completed from battery through both windings of magnet 318, lowermost conductor and contact of link 313, conductor 353, left inner armature and back contact of relay 210 to ground at the left inner armature and front contact of relay 208. Relay 208 at this right outer armature and contact also maintains ground on sleeve conductor 321 and thence by means of contacts in switch 300 to the sleeve conductor of the line, to render the same busy should this line be idle at the time. It will be remembered in the preceding description, there was a substitute holding circuit for relay 209 which extended through the called subscriber's loop. However, since relay 209 does not operate when key 119 is operated, this holding circuit is rendered ineffective; consequently, the operator may release the connection immediately that release key 113 is restored without waiting for the interrupter 212 to function.

A description will now be given of the sequence of operations in the establishment of a local connection necessitating the use of one of the regular incoming selector switches 200. For this purpose it will be assumed that the subscriber of line 100 desires to converse with the subscriber of line 307, both of which lines are located in the same exchange. The removal of the receiver by the calling subscriber causes line 100 to be extended, by means of the automatic operation of line switch 101, through the district trunk 102 to the district switch 103. At this time also sender selector 104 is actuated to associate an idle register sender with the calling line. The association of a sender with the calling line causes the actuation of a connector similar to connector 400, resulting in the association of an outing marker with the calling line. After the marker has thus been associated, the district selector switch 103 is selectively operated under control of the office code as recorded in the marker resulting in the selection of an idle

trunk as 115 leading to a local incoming switch as 200. When such a trunk has been selected the outgoing marker and sender connector release and a second sender connector 400 is actuated to associate the sender with an idle incoming marker such as is partly shown in Fig. 4. The numerical portion of the called line designation is now transferred from the sender registers to the registers of the incoming marker wherein it is translated to cause the selective operation of the connecting device 502. A record of the incoming frame to which trunk 115 leads having been recorded in the sender the marker is now caused to select and actuate the proper incoming frame connector 500, resulting in the operation of vertical magnet 237. The translation of the marker also brings about the actuation of the vertical magnet 306 controlling the vertical row of contacts in which the called line appears, and since the called line 307 is located in section 310 of the connector switch, relay 506 is operated. Since the group of trunks required to complete extension to the called line has been definitely located as leading from incoming switch 200 to connector switch 300 the trunk connecting device 501 is selectively operated to associate this group of trunks with the marker testing mechanism.

It will be assumed that the trunks appearing in vertical row 216 compose the group leading to the connector group having access to the called line. Only three of these trunks have been shown, but it will be understood that the number will be in proportion to the requirements of the traffic conditions.

As hereinbefore mentioned trunk 220 is the last trunk in the group appearing in vertical row 216. The marker now performs a test of the horizontal links in switch 200, of the trunks 219, 220, etc. and also of the horizontal links in section 310 of connector switch 300 in substantially the same manner to that previously described in connection with an interoffice call. In this case, however, since the trunk groups are relatively large and trunk connector 501 is operated in place of relays such as 503, 504, etc., the maximum number of test relays corresponding to a maximum number of trunks in a group is required. From an inspection of the figures it will be seen that the test circuits for the trunks in this instance, however, are substantially similar to those described in connection with the operation of switch 201, except that these circuits are now completed through contacts of device 501, instead of through contacts of a relay such as 503, 504, etc. It will be further observed that none of the relays 503, 504, etc. are operated in this case because of the fact that relay 404 in the marker is not energized. The reason relay 404 is not energized at this

time is because the relay 109 in the sender has not been previously operated. If the test reveals the fact that link 235, trunk 220 and link 313 are simultaneously idle relay 419 is operated in a circuit traceable from ground through the right inner armature and contact of relay 402, right inner armature and back contact of relay 404, left armature and front contact of relays 408, 10 409, 410 in series, left armature and back contact of relay 411 to battery through the winding of relay 419. Relay 419 operates in the manner hereinbefore described and causes the operation of horizontal magnets 15 236 and 318 whereby the connection is extended through switches 200 and 300 to the called subscriber's line 307.

The release of a connection after the termination of conversation is substantially 20 similar to that described in connection with interoffice call.

From the foregoing description it will be seen that in certain classes of connection wherein incoming switches of the type of 25 switch 200 are employed a simultaneous test is made of a selected trunk group to determine the first idle one thereof for the purpose of completing a connection thereover. This selected idle trunk obviously may be located at any point in the group. In the class of connection requiring the use of an incoming switch similar to switch 201 a particular trunk in each of these trunk groups must be selected, namely, the last one 30 thereof, thus allowing one trunk in each of the trunk groups outgoing from the regular incoming switches to be used for both local connections and interoffice connections requiring the service of an operator.

40 Certain other features of invention disclosed in the drawing but not claimed in this application are being claimed in a copending application of E. S. Gibson, Serial No. 726,241, filed July 16, 1924.

45 What is claimed is:

1. In a telephone exchange system, a calling line, an operator's position, a first selective switch for extending said calling line, a second selective switch, a group of trunks 50 interconnecting said first and said second selective switches, means under control of said calling line for selectively operating said first selective switch to seize any trunk in said group of trunks and means under control of said operator's position for seizing a particular trunk in said group of trunks.

60 2. In a telephone exchange system, a calling line, an operator's position, a first selective switch for extending said calling line, a second selective switch, a group of trunks 65 interconnecting said first and said second selective switches, means under control of said calling line for selectively operating said first selective switch to seize an idle trunk in said group of trunks and means un-

der control of said operator's position for seizing a particular trunk in said group of trunks.

3. In a telephone exchange system, a calling line, an operator's position, a first selective switch for extending said calling line, 70 a second selective switch, a group of trunks interconnecting said first and said second selective switches, means under control of said calling line for selectively operating 75 said first selective switch to seize any trunk in said group of trunks and means under control of said operator's position for seizing only the last trunk in said group of trunks.

4. In a telephone exchange system, a calling line, an operator's position, a first selective switch for extending said calling line, a second selective switch, controllable from 80 said calling line and from said operator's position, a group of trunks inter-connecting said first and said second selective switches, means under control of said calling line for selectively operating 85 said first selective switch to seize the first idle trunk in said group of trunks, and means under control of said operator's position for seizing a particular trunk in said group of trunks without operating said first mentioned selective switch.

90 5. In a telephone exchange system, a calling line, an operator's position, a first selective switch for extending said calling line, a plurality of second selective switches, 95 groups of trunks inter-connecting said first selective switch and said plurality of second selective switches, means under control of said calling line, for marking a particular one of said groups of trunks, means for selectively operating said first selective switch to seize any trunk in said marked group, 100 and means under control of said operator's position for seizing a particular trunk in any of said plurality of groups of trunks.

105 6. In a telephone exchange system, a calling line, an operator's position, a first selective switch for extending said calling line, a plurality of second selective switches, groups of trunks inter-connecting said first selective switch and said plurality 110 of second selective switches, means under control of said calling line for marking a particular one of said groups of trunks, means for selectively operating said first selective switch to seize any trunk in said marked group, and means under control 115 of said operator's position for seizing only the last trunk in any of said plurality of groups of trunks.

120 7. In a telephone exchange system, a calling line, an operator's position, a first selective switch for extending said calling line, a second selective switch, controllable from 125 said calling line and from said operator's position, groups of trunks inter-connecting said first and said second selective switches,

means under control of said calling line for seizing any trunk in any of said groups of trunks, and means under control of said operator's position for seizing a particular 5 trunk in any of said groups of trunks.

8. In a telephone exchange system, a calling line, an operator's position, a first selective switch for extending said calling line, a second selective switch, controllable from 10 said calling line and from said operator's position, groups of trunks inter-connecting said first and said second selective switches, means under control of said calling line for seizing any trunk in any of said groups of 15 trunks, and means under control of said operator's position for seizing the last trunk in any of said groups of trunks.

9. In a telephone exchange system, a calling line, an operator's position, a first selective switch for extending calls originating on said calling line, a second selective switch, for extending calls originating at said operator's position, a third selective switch accessible in common to said first and said second 25 selective switches, a group of trunks inter-connecting said first selective switch and said third selective switch, a particular trunk in said group also interconnecting said second selective switch and said third selective 30 switch, means under control of one of said calling lines for selectively operating said first selective switch to seize the first idle trunk in said group of trunks, and means under control of said operator's position of 35 seizing said particular trunk in said group of trunks.

10. In a telephone exchange system, calling lines, an operator's position, a first selective switch for extending calls originating on said calling lines, a second selective switch for extending calls originating at said operator's position, a third selective switch accessible in common to said first and said second selective switches, a group 40 of trunks interconnecting said first and said third selective switches the last trunk in said group also interconnecting said second and said third selective switches, means under control of one of said calling lines 45 for selectively operating said first selective switch to seize the first idle trunk in said group of trunks, and means under control of said operator's position for seizing only the last trunk in said group of trunks.

55 11. In a telephone exchange system, calling lines, an operator's position, a first selective switch for extending calls originating on said calling lines, a second selective switch for extending calls originating at said operator's position, a third selective switch accessible in common to said first and said second selective switches, a group of 60 trunks leading to said third selective switch, a particular trunk in said group being accessible in common to said first and said 65

second selective switches, means under control of one of said calling lines for selectively operating said first selective switch to seize the first idle trunk in said group of 70 trunks, and means under control of said operator's position for seizing only said common trunk in said group of trunks.

12. In a telephone exchange system, a calling line, a called line, an operator's position, a first selective switch for extending said calling line, a second selective switch, a group of trunks interconnecting said first and said second selective switches, means under control of the calling line for seizing any one of said trunks, means under control 75 of said operator's position for seizing a particular trunk in said group of trunks, means for maintaining a busy condition on said called line, and means effective when said particular trunk has been seized for operating said second selective switch under control of said operator's position to complete the extension of said calling line to said called line while said called line is being 80 maintained busy.

13. In a telephone exchange system, a calling line, a called line, an operator's position, a first selective switch for extending said calling line, a second selective switch controllable from said calling line and from 95 said operator's position, groups of trunks extending between said first and said second selective switches, means for maintaining a busy condition on said called line, means under control of said calling line for 100 seizing an idle trunk in any of said groups of trunks, means under control of said operator's position for seizing a particular trunk in any of said groups of trunks and for selectively operating said second selective switch to seize said called line while it is being maintained busy.

14. In a telephone exchange system, a subscriber's line, an operator's position, a first selective switch for extending connections from said line, a second selective switch for extending connections to said line, groups of trunks leading to said second selective switch, means under control of said first selective switch for maintaining said 110 line busy, a third selective switch, means under control of said operator's position for operating said third selective switch to seize a particular trunk in said group of trunks and for operating said second selective 115 switch to complete a conversational connection to said line while it is being maintained busy by said first selective switch.

15. In a telephone exchange system, a subscriber's line, an operator's position, a first selective switch for extending connections from said line, a second selective switch for extending connections to said line, groups of trunks leading to said second selective switch, means under control of 120 125 130

- said first selective switch for maintaining said line busy, a third selective switch, means under control of said operator's position for operating said third selective switch to seize a particular trunk in said group of trunks and for operating said second selective switch to complete a conversational connection to said line regardless of the busy or idle condition of said line.
16. In a telephone system, a telephone line, a selective switch, a group of trunks, means for operating said switch to extend

connections over said trunks, an operator's position, a marker for testing said trunks and for controlling the operation of said switch, means under control of said operator for governing said marker to cause the extension of a connection over a particular one of said trunks to said line regardless of the condition of said line. 20

In witness whereof, I hereunto subscribe my name this 14th day of July, A. D. 1924.

SAMUEL B. WILLIAMS.
